(57) **CLAIM**

The ornamental design for keyboard with multimedia display and roller module, as shown and described.

DESCRIPTION

FIG. 1 is a perspective view of a keyboard with multimedia display and roller module showing our new design;

FIG. 2 is a top plan view thereof;

FIG. 3 is a rear elevational view thereof;

FIG. 4 is a left side elevational view thereof;

FIG. 5 is a right side elevational view thereof;

FIG. 6 is a front elevational view thereof; and,

FIG. 7 is a bottom plan view thereof.

The phantom lining where utilized is for illustrative purposes only and is not intended to limit the claimed component design to the features shown in phantom.
